UNITED STATES PATENT OFFICE.

ARTHUR WALTER SAUNDERS, OF LEEDS, ENGLAND.

WASHING-BOARD.

1,096,957.

Specification of Letters Patent. Patented May 19, 1914.

Application filed July 7, 1913. Serial No. 777,672.

To all whom it may concern:

Be it known that I, ARTHUR WALTER SAUNDERS, a subject of the King of Great Britain and Ireland, residing at 1 Nursery 5 Mount, Woodhouse Hill, Leeds, in the county of York, England, have invented new and useful Improvements in or Relating to Washing-Boards, of which the following is a specification.

10 This invention relates to improvements in washing boards provided with a corrugated surface upon which the clothes to be washed are soaped, rubbed or scrubbed with a brush.

15 It is an object of this invention to provide an improved, simplified, and economical construction of washing board of this character utilizing brushes or the like for retaining the soap upon the board where it will have the most effect upon the clothes being 20 washed.

According to this invention the rubbing or scrubbing board is formed as hitherto of a wooden or other frame in which the two side pieces project below the bottom of 25 the rubbing or scrubbing surface,—hereafter termed “rubbing surface,”—and the rubbing surface is formed in sections of transverse horizontal corrugations or flutes formed either wholly or partially of wood, zinc or 30 other material in one or more pieces secured together by any suitable means. In this arrangement the convex or arched portions of 35 one of the rubbing surfaces are arranged to be opposite the concave or indented portions of the rubbing surface on the opposite side of the board.

At a suitable distance between the top and bottom sections of the rubbing surfaces is 40 inserted a corrugated portion provided with a number of horizontal rows of bristles to form a brush which extends the full width of the said surface, and forms the means for retaining the soap at or about the center of the washing portion of the board.

45 In the drawings hereunto annexed Figure 1 is a front elevation of a washing board constructed according to this invention; Fig. 2 is a sectional elevation of the same on line A, B, Fig. 1; Fig. 3 is an enlarged 50 part sectional elevation showing the brushes with the corrugations above and below them.

The washing board consists of the two sides *a*, *a*, the top rail *b* provided with the handles *c*, *c*, and the bottom rail *d*.

55 In practice the sides *a*, *a* are formed, say, rectangular in cross section with a groove *e*

cut in each of the inner sides for a suitable depth from the top rail *b* to the bottom rail *d*, and the sides are made to project below the bottom rail as shown at Fig. 1 in order 60 that they may be inserted in a washing tub or tray and permit of the rubbing surface being readily above the upper edge of the said tub or tray. The top rail *b* and the bottom rail *d* are each made in any suitable 65 shape, such as round, or square, and in each of the said parts is respectively cut the transverse groove *f* and *g* for purposes to be presently described. The ends of the sides *a* are respectively mortised or otherwise secured to the top rail *b* and the bottom rail *d*. 70

In the vertical grooves *e*, *e* in the sides *a* is inserted a center board *h* made in two portions which extend respectively from the 75 top rail *b* to the top of the center section *i* in which the tufts of bristles,—which form the brushes *j*, *j*,—are placed, and from the underside of the center portion to the groove *g* in the bottom rail *d*. The two portions 80 of the center board *h* are placed,—as shown at Fig. 3,—between the corrugated surfaces of the rubbing surface *k*. The rubbing surfaces *k*, *k* are formed of either wood, zinc or other material, and the sides and ends 85 thereof are made to pass respectively into the grooves *e*, *f*, and *g*, and are held in position by the said grooves. In the drawings the rubbing surfaces *k*, *k* are formed of a sheet of zinc cut to the required size bent 90 so as to form the two rubbing surfaces of the washing board and to permit of the center board passing between them, as shown at Fig. 3.

It will readily be seen that the lower edge 95 of the upper portion of the rubbing surface *k* is bent inward and upward to form the V-shaped horizontal groove *l* shown for receiving and holding in position the upper end of the center section *i* which is shaped 100 to fit it, and the upper edge of the lower section *k* is similarly V-shaped only in the opposite direction for receiving the lower edge of the said center section.

In this invention instead of having the 105 projections or convex portion of the rubbing surface on the same level on both sides of the board, they are arranged to be opposite to each other. That is to say, the convex portion *n* on one side of the board is opposite to the concave portion *o* on the other side. The projections of the upper and 110

lower rubbing surfaces on the opposite sides of the washing board are staggered so that there may be uniformity in the spacing apart of the corrugations throughout the 5 entire length and on both sides of the board.

The center portion *i* is preferably, though not necessarily so, made of wood, and the tufts of bristles *j* are inserted in horizontal rows in the concave portion of each corrugation. As is clearly shown in Fig. 3, the center portion *i* is formed at either side with alternate grooves and projections which are staggered on the opposite sides of the section. The tufts of bristles are seated in the 10 staggered grooves or concave portions at the opposite sides of the section so that they may be set in to a considerable distance without impairing the strength of the section.

The tufts or bristles *j* are arranged at suitable 20 distances apart in each row, and the bristles on one side of the board may be of different strengths or thicknesses from the bristles on the opposite sides so that a hard or soft brush may be formed one on each side so as to be suitable for fine or delicate goods as well as for strong or coarse goods. If desired the strength or thickness of the tufts may be varied in each row or in the successive rows. In the drawings five 25 rows of bristles are shown on each side of the center section, but this number may be varied as circumstances require. That is to say, the number may be either reduced or increased as circumstances or the class of goods,—for which the washing board is used,—require. The rows of bristles are made to extend the full width of the rubbing surface and the tufts may be more or less widely spaced. The center board *h* 30 forms a stiffening piece for the corrugated surfaces *k* when they are formed of zinc or other sheet metal. The tufts of bristles form a ready means for retaining the soap at a suitable distance from the top of the board

and thereby prevent it running down the 45 same, and mixing with the other liquid before there has been an opportunity of utilizing it for washing and cleansing purposes. The tufts of bristles also provide a ready surface for assisting in removing the dirt, 50 or other impurity from the clothes during the washing operation. The clothes to be washed are laid over the corrugated surfaces *k*, *k*, and after being soaked in water, and the soap placed in the brush portion 55 *i*, the clothes are rubbed or scrubbed thereon until they become clean.

What I claim is:—

1. In a washing board, a frame, a middle section in the frame, and upper and lower 60 sections in the frame, each of said upper and lower sections comprising a single corrugated sheet of metal returned upon itself and bent at its overturned portion into a socket for the reception of the adjacent edge 65 of said middle section.

2. In a washing board, corrugated end sections, a middle section interfitting between the end sections and having alternate corrugations in its opposite sides, and tufts 70 of bristles carried by the middle section, said tufts of bristles being seated in the alternate grooves of the middle section whereby the tufts may be seated relatively deep into the middle section without impairing the strength of the same. 75

3. In a washing board, a section alternately corrugated at its opposite sides, and tufts of bristles carried by the section, said tufts being seated in the alternate grooves of 80 said section whereby the tufts may be seated relatively deep into the section without impairing the strength of the same.

ARTHUR WALTER SAUNDERS.
